To all whom it may concern:

Be it known that I, Robert C. Stahler, a citizen of the United States of America, residing at Portsmouth, in the county of Scioto and State of Ohio, have invented a new, original, and ornamental Design for an Animal Feeder, of which the following is a specification, reference being had to the accompanying drawing, forming part thereof.

Figure 1 is a perspective view of an animal feeder, showing my new design.

Fig. 2 is a side elevational view.

I claim:

The ornamental design for an animal feeder, as shown.

ROBERT C. STAHLER.
